UNITED STATES PATENT OFFICE.

RICHARD A. MIRZAN, OF SYRACUSE, NEW YORK.

MEANS FOR ANCHORING BOLTS.

Application filed March 6, 1926. Serial No. 92,822.

This invention relates to improvements in bolt anchors, designed for securing bolts and rods to stone, brick and concrete construction, and has for its object to provide a simple, inexpensive and efficient anchoring means, adapted for use in connection with either new or old masonry work. A further object is to provide reliable and extremely powerful anchoring means, which may be applied to bolts or rods of different size, and wherein the bolts may be adjusted either before or after the parts have been embedded in the work. A further object is to provide an anchor comprising a number of similar units, which may be employed singly or collectively, and are preferably threaded for facilitating their ready and positive attachment to the bolts; the said units preferably being so constructed and arranged as to expand radially under stress exerted by the bolts, as for example, when the latter are subjected to great strains longitudinally, for preventing yielding movement or withdrawal of the bolts. Each unit of the anchor preferably comprises a central body and a plurality of arms which radiate from the body, the said arms being inclined upwardly at suitable angles relatively to the axis of the central body, for enabling the said units to be stacked and closely interfitting; each of the several arms of the units comprising an oblong core of steel or iron preferably rectangular in cross-section, and the said cores preferably being uniformly and wholly encased in a leaden envelop or jacket, which may be integral with the central body, by which the bars are suitably spaced and adjustably secured to the bolt.

I attain these objects by the means set forth in the detailed description which follows, and as illustrated by the accompanying drawing, in which—

Figure 1 is a partial side elevation and partial central longitudinal section of one form of my invention, showing a bolt fitted with separable anchoring units that are embedded in concrete work. Fig. 2 is a top plan view of one of the units of the anchor. Fig. 3 is an elevational view, showing a number of anchoring units having a greater number of radiating arms collectively enveloped in a jacket of lead. Fig. 4 is a broken top plan view of the same. Fig. 5 is respectively a plan, and an end view, of one of the

hard metal elements. And Fig. 6 is respectively a top plan and a central vertical section of a slightly modified anchoring unit.

In the drawing, 2 represents a bed or slab of concrete, in which has been drilled a hole 2', for the bolt 3 and the anchor, the latter being designated generally by the numeral 4. According to Figs. 1 and 2, the anchor 4 comprises a number of similar units or sections, as 4', each of which consists of a star-shaped envelop 4^a, preferably made of lead, and having radial arms 4^b, in which are embedded oblong bars of steel or iron, as 5, as best seen in Fig. 2. The circular body portions 4^c of the units may be cast with central openings, as 4^d, the said openings being preferably smaller than the diameter of the bolt 3, so that the said openings may be reamed out and threaded, for application to the threaded portion 3' of the bolt, like a nut. For different size bolts, the bars 5, as well as the pliable jackets 4^a, and the openings 4^d, may be suitably proportioned for the several sizes. In all cases, however, it is preferred to so dispose the bars 5, that their inner or facing ends project into the path of the tap, by which the central openings 4^d are threaded. By this arrangement, the harder and stiffer cores 5 become intimately interlocked with the threads of the bolt 3, and enables the units to withstand radial thrusts, when longitudinal stress is applied to the bolt, as in the direction of the arrows in Figs. 1 and 3. The arms 4^b of the units 4' are preferably disposed at an angle (for example 30°) to the horizontal, as shown in Fig. 1, and when a number of units are required, in order to afford adequate anchorage for certain construction work, the units may be readily stacked in close order, as shown in Fig. 1, and all said units being similarly threaded, the whole stack may be screwed on to the bolt 3, like a nut, before the device is set in the socket or opening 2' of the concrete. When the bolt with the anchor 4 applied is suitably positioned in the hole 2', the latter is usually filled with grout, indicated at 2". The grout is usually semi-liquid and readily searches out and fills all the joints and crevices of the anchor as well as the cavities of the adjacent concrete walls, and when the grout becomes set, the bolt and related parts are immovably held in place. The leaden en-

velop 4^a has for its primary object to provide a convenient and suitable support for the independent bars 5.

By forming the outer ends of the arms 4^b square and inclining the arms, the ends of the corresponding arms when several units are stacked, as shown in Fig. 1, present serrated faces, as 4^c, which serve to correspondingly mold the grout or concrete, there-
10 by effecting an interlocking of the units with the concrete, which of itself offers great resistance to the dislodgment of the bolt and anchor. These serrated joints provide for the several arms 4^b similar solid abutments
15 or sockets 2^x, which tend to resist radial thrust of the arms, and which greatly increases the anchorage. This latter resistance is heightened to a considerable extent by the close stacking or serried ar-
20 rangement of the arms. By this construction and arrangement, strains exerted longitudinally of the bolt are communicated to and apportioned between the radial arms of the units, which in turn exert their proper
25 proportion of the bolt-strains substantially in the direction of the inclined planes of the arms, and accordingly directly against and at right angles to the abutments 2^x, and in case the stress on the bolt is increased to an
30 extraordinary degree that not even the concrete may withstand, the latter will tend to shear or fracture along the oblique lines 2^d (see Fig. 1). In such event the bolt, together with a relatively large inverted cone-
35 shaped fragment of the concrete lying above the lines 2^d, will become detached from the main bed or slab 2.

The modification shown in Figs. 3 and 4, consists principally of increasing the number of radial arms or ribs, as 6, and casting a single envelop, as 6', that embraces and conceals all of the hard metal cores, as 5^a, which may follow the construction shown in Figs. 1 and 2. By this modification, the
45 anchor may be handled as one part, and is preferably threaded throughout its length for screwing on to the bolt 3^c. The several bars 5^a preferably make threaded contact with the bolt, as shown in Fig. 4. This unitary anchor is suitable for extremely heavy work, that is capable of substantially exact computation for predetermining the size and strength of the anchor, and is not subject to alteration for either decreasing or in-
55 creasing the dimensions of the anchor. In applying the envelop 6', the outer faces 6^a, of the radial ribs 6 are preferably serrated, the same as the lighter anchor of Figs. 1 and 2, and when this unitary anchor is called
60 upon to resist longitudinal stress of the bolt 3^c, the serrated portions 6^a, of the ribs 6 become interlocked with the correspondingly shaped abutments 2^x, and as these abutments all face toward the axis of the bolt and anchor, they effectually resist the longi-

tudinal displacement of the anchor. The hard metal cores 5^a form a rigid bridge or brace between the bolt and the abutments 2^x, and the said braces being disposed at right angles to the faces of said abutments and being spaced equidistantly around the bolt, as shown in Fig. 4, the anchor is capable of resisting the greatest strains the bolt and concrete may withstand, without destruction of one or the other of said parts. 75

In Fig. 6 is illustrated an anchor unit 7, which preferably comprises one part of any suitable metal, having a number of arms 7' that radiate from a threaded concentric opening 7^a for detachably applying the unit 80 to a bolt as 3^d, the said arms preferably being formed at an angle similar to the arms 4^b, and being supported and connected by webs 7^c that lie in the planes of the arms.

Having thus described my invention, 85 what I claim, is—

1. An anchoring unit for screw bolts, comprising a concave arrangement of metallic bars spaced equidistantly to form a central opening, the corresponding ends of said bars being threaded for attachment to a bolt, the said bars being embedded and held in place by a matrix of softer material (e. g. lead), and the said unit and the corresponding portion of the bolt adapted to 95 be embedded in concrete.

2. A composite anchor for bolts and the like, comprising a number of units of the character set forth in claim 1, said units being superposed one upon the other in mutual contact and being held together by a common jacket of softer material, which envelopes the several units, and the said units having registering central openings for attachment to the bolt. 100

3. An anchor unit comprising a plurality of arms that radiate from a ringlike body portion, the latter being threaded for interlocking the unit to a bolt, said arms being correspondingly inclined upwardly relatively to the axis of the bolt, and corresponding parts of the bolt and said unit adapted to be embedded in concrete. 110

4. An anchor unit comprising a plurality of metallic bars arranged radially from a center to form an opening, the inner portions of the bars at the opening being threaded for interlocking the unit to a bolt, the said bars being connected at their inner ends by a common ring-like body adapted to hold the bars in contact with the bolt, and said bars being correspondingly inclined relatively to the axis of the bolt, a number of the units adapted to be superposed upon each other for increasing the anchorage of the bolt, and said anchor and the corresponding portion of the bolt adapted to be embedded in concrete. 115

5. An expansible anchor for bolts and the like, comprising an annular body of soft 120

metal having its inner circumference threaded for receiving the threaded portion of a bolt, and having radial arms reinforced by cores of hard metal, the inner ends of said cores coinciding with the inner circumference of the body, said cores being wholly enveloped by the material of said body and arms, and said arms when molded being disposed at an inclination to the plane of said body portion for resisting longitudinal movement of the bolt.

6. In an anchor for bolts and the like, the combination with a threaded bolt adapted to be embedded in a slab of concrete, of an anchor comprising a plurality of similar units, each unit consisting of a body of non-ferrous metal having a central threaded opening for attachment to the bolt, and having radial arms that incline upwardly, cores comprising oblong bars of ferrous metal reinforcing said arms and being entirely enveloped by the material of the body and arms and in direct contact with the bolt, the said units adapted to be stacked in close relation, and the arms of the several units registering and forming ribs with serrated faces that become interlocked with the concrete and resist longitudinal movement of the bolt and anchor.

7. An anchor for bolts and the like, comprising a plurality of similar units, each unit comprising a central body of lead having a plurality of radial upwardly inclining arms, said units adapted to be stacked, the corresponding arms of the units overlying each other and forming similar longitudinal ribs whose free extremities are serrated and adapted to become interlocked with concrete or grout when the anchor is embedded therein, said central body being internally threaded for attachment to the threaded portion of a bolt, and stiff ferrous metal cores embedded in and reinforcing the leaden arms, and said cores being in direct contact with the threads of the bolt.

8. The combination with a bolt having a

threaded portion adapted to be embedded in concrete, of a plurality of superposed anchoring units having similar body portions bored out and threaded for attachment to the bolt like nuts, each body being formed with a plurality of radial arms, said body and arms consisting of pliant tenacious metal, and the said arms being bent upwardly at corresponding angles to the plane of the body, and bars of hard metal like the bolt being embedded in said arms, said bars being in direct contact with the threads of the bolt and reinforcing the pliable arms adapted to thrust radially for resisting dislodgment of the bolt.

9. The combination with a bolt having a threaded portion adapted to be embedded in concrete, of a plurality of anchoring units comprising ring-like bodies internally threaded for attachment to the bolt, and having radial arms inclining upwardly, said bodies and their arms being composed of lead-like metal and adapted to be applied to the bolt like nuts, and reinforcing cores of metal of the hardness of the bolt, being encased in said arms, the inner ends of said cores being in direct contact with the threads of the bolt and their sheathed outer ends being embedded in the concrete and resisting dislodgment and withdrawal of the bolt when the latter is subjected to longitudinal stress.

10. An anchor unit comprising a plurality of metallic bars that radiate from a ring-like body, the corresponding ends of said bars being embedded in the body, the inner circumference of said body and the said ends of the bars being threaded for interlocking the unit to a bolt, said unit and the threaded portion of the bolt adapted to be embedded in concrete, and said body adjacent said bars adapted to flex for enabling the bars to thrust radially when the bolt is subjected to longitudinal stress.

In testimony whereof I affix my signature.
RICHARD A. MIRZAN.
